US00D407379S

United States Patent [19]**Schwaegerle****Patent Number: Des. 407,379****Date of Patent: **Mar. 30, 1999**[54] **ELECTRIC FOOT SWITCH**

2443357 4/1975 Germany .

[75] Inventor: **Gary G. Schwaegerle**, Cincinnati, Ohio**OTHER PUBLICATIONS**[73] Assignee: **Reliance Medical Products, Inc.**,
Mason, OhioReliance Medical Products, Inc., 7000, *Flexibility for Examinations or Minor Procedures*, Brochure, 1994.[**] Term: **14 Years**Reliance Medical Products, Inc., 980, *The Chair That's a World Power*, Brochure, 1993.[21] Appl. No.: **84,824***Primary Examiner*—Brian N. Vinson
Attorney, Agent, or Firm—Wood, Herron & Evans, L.L.P.[22] Filed: **Mar. 11, 1998****CLAIM**[51] LOC (6) Cl. **13-03**

The ornamental design for an electric foot switch, as shown and described.

[52] U.S. Cl. **D13/167****DESCRIPTION**[58] Field of Search **D13/167; 200/52 R, 200/61.09, 86.5, 61.89**

FIG. 1 is a front perspective view of the electric foot switch; FIG. 2 is a top view thereof;

FOREIGN PATENT DOCUMENTS

FIG. 5 is a rear view thereof;

- 58181 9/1953 France .
 2399926 3/1979 France .

FIG. 6 is a bottom view thereof;

FIG. 7 is a front perspective view of an alternative embodiment of the electric foot switch with an actuator knob and recess portion shown in broken lines;

FIG. 8 is a top view of the electric foot switch as shown in FIG. 7;

FIG. 9 is a front view of the electric foot switch as shown in FIG. 7;

FIG. 10 is a right side view of the electric foot switch as shown in FIG. 7 with the left side being a mirror image of the right side; and,

FIG. 11 is a rear view of the electric foot switch as shown in FIG. 7.

The broken line portions of FIGS. 6-11 are to show illustrative or environmental structure which forms no part of the invention as claimed in these specific figures.
